UNITED STATES PATENT OFFICE

DONALD G. LITTLE, OF WILKINSBURG, PENNSYLVANIA, ASSIGNOR TO WESTINGHOUSE ELECTRIC & MANUFACTURING COMPANY, A CORPORATION OF PENNSYLVANIA

VACUUM-TUBE SYSTEM

Application filed January 25, 1924. Serial No. 688,383.

My invention relates to radio frequency generating systems.

One object of my invention is to provide means for increasing the efficiency of a generator for producing modulated, radio-frequency currents.

Another object of my invention is to provide means for use in connection with a radio-frequency oscillation generator and modulator apparatus which will increase the efficiency of operation of both the generator and the modulator in the production of modulated, radio-frequency oscillations.

Another object of my invention is to provide means for damping out the very high frequency parasitic oscillations in a triode which the internal capacity of the triode tends to produce when combined with connected inductance and capacity in exterior circuits, without reducing the flow of normal frequency currents.

In the operation of high-power radio-frequency oscillation generators using a plurality of triode thermionic discharge devices connected according to the Heising constant-current modulation system with the very low impedance triodes and the high voltages which are essential for the conversion of a considerable quantity of power into the form of modulated radio-frequency oscillatory energy, difficulty has been encountered in obtaining satisfactory efficiency and satisfactory purity of vibration frequency.

In the prior art of the operation of triode devices, it has been found desirable for many purposes to insert into the grid circuit of the device various impedances. In many instances, the impedance device inserted consisted in part of a condenser and in part of a high resistance. This resistance served to maintain the average mean voltage difference between the grid and cathode at a value to cause the device to function in a predetermined way. In each case, the resistance was shunted by a condenser which passed alternating current freely. By this means, the grid was maintained at a desired potential without restraining the access of alternating current to it. When such resistances were used, they were customarily connected in

shunt to some other impedance in the same circuit and ranged in value from 100,000 ohms to one or more megohms.

It has been found that a considerable amount of electrostatic capacity is present between the various connected circuits of such a triode operating system. This capacity, in conjunction with the capacity of the tube itself, and the inductance of the various circuit elements to which it is connected produce a condition which tends to cause each triode to oscillate independently at an extremely high parasitic frequency. This parasitic oscillation is objectionable because of the waste of power which it causes and because of the heating which it produces in the triode, and, also, because of the possibility of some of it being radiated by the same system which generates and radiates the signal wave and thereby producing an impure radiated wave.

The device of my invention is a means which substantially prevents these parasitic oscillations, both in oscillator triodes and in modulator triodes.

Other objects and structural details of my invention will be apparent from the following description when read in connection with the accompanying drawings, wherein

Figure 1 is a diagrammatic view of a radio-sending apparatus comprising my invention, and

Fig. 2 is a diagrammatic view of the elements of a triode and its connected circuits and the capacities and inductances in those circuits.

Referring to Fig. 1, a radio-sending aerial 1, a connected inductance 2 and a ground 3 comprise an elementary radiating system. To this system is connected a pair of oscillator triodes 4 and 5 having anodes, grids and cathodes. The drawing further shows another pair of triodes 6 and 7 connected as modulators, a direct-current source 8, an inductance 9, a modulation transformer 11 and a source of filament heating current 12. These various elements are connected, as indicated, by conductors, as required for constant current modulation systems. In the grid leads of triodes 4, 5, 6 and 7 are connected resistors 100

14, 15, 16 and 17, which are the means that aid in reducing the parasitic oscillations.

In Fig. 2, a triode 21 is represented having a grid 22, an anode 23 and a cathode 24. To the anode 23 is attached an inductance 25 and a connecting conductor 26. To the grid 22 is attached an inductance 27 and a connecting conductor 28. Inductances 25 and 27 are indicative of the inductance present in any circuit, even a straight wire. To the cathode 24 is connected a conductor 29. A capacity equivalent to that between lead 26 and lead 29 is indicated by a condenser 31. The capacity between leads 28 and 29 is indicated as a condenser 32. The capacity between the grid 22 and the anode 23 is indicated as a condenser 33. In the circuit between the grid 22 and the inductance 27 is indicated a resistor 34. Similar grid leads to triodes 4, 5, 6 and 7 are indicated at 35, and plate leads at 36.

The circuits and apparatus shown in Fig. 2, comprising the triode 21 having a low internal impedance, constitute a system in which oscillations may be generated upon the application of sufficiently high voltage to the triode. The inductance 25 serves as a plate inductance, the inductance 27 serves as a grid inductance, condensers 31 and 32 in series serve as a portion of a circuit for high-frequency between the inductance 25 and 27, and condenser 33 serves as a means for completing a circuit whereby energy is transferred from the inductance 25 to the grid 22. The capacity 33 cooperates with the inductance 27 to impress voltage changes upon grid 22 in the proper phase displacement to cause the triode 21 to be set into a condition of oscillation at a frequency determined by the values of inductance and capacity in the circuits.

In the system of Fig. 2, a resistance 34 is connected between the grid 22 and the grid lead 28. This resistance, so connected, is in a position intermediate the capacity 33, which is the capacity of the triode 21 and inductance 27 of the grid conductor of the triode. This resistance 34 is a damping resistor which limits the current flow to grid 22. This limiting effect damps out undesired high-frequency oscillations because of the fact that the generation of such oscillations is possible only because of the flow of oscillatory energy through the capacity of tube 21.

In the development of the normal desired oscillation frequency in a triode system, the capacity of the triode plays a very subordinate part in the necessary transfer of voltage to the grid to produce oscillation. Instead, the energy is furnished by coupling between the grid and plate coils. For this reason, a very limited amount of current flows to the grid for the production of the oscillations of the desired frequency. Because of this fact,

a resistor in the grid circuit exercises a proportionately greater damping action on the undesired frequency than on the desired frequency, since the energy of the undesired frequency must all be transferred through the tube capacity and the grid lead while the desired energy is not so transferred. The ratio can be still further increased by increasing the effective voltage applied to the grid from the grid inductance by increasing the connected turns of the grid coil. This increase of voltage compensates for the small amount of energy lost in the resistance.

In the oscillator system represented in Fig. 1, which is designed for the generation of a customary radio frequency, inductances 25 and 27 may be represented by straight conductors 35 and 36. It is not necessary for radio-frequency oscillations that the inductance be in the form of actual coils. Under these conditions, the same straight conductor forms both a part of a condenser and an inductance as well. This condition is present in the typical radio-frequency generating apparatus, as will be evident from Fig. 1.

The resistors 14, 15, 16 and 17 in Fig. 1 perform the function for their respective triodes 4, 5, 6 and 7 that is indicated as the function of resistance 34 of Fig. 2. The values of these resistors may be between 10,000 ohms and 50,000 ohms for most effective operation.

By this means, I am able to reduce to a negligible magnitude the parasitic oscillations developed in the triodes of a modulator system because of the internal capacity of the triodes and thereby reduce the energy loss and heating in such triodes without interference with their operation for the generation of oscillations at a lower desired frequency.

While I have shown only one embodiment of my invention in the accompanying drawings, it is capable of various changes and modifications without departing from the spirit thereof, and it is desired, therefore, that only such limitations shall be imposed thereon as are indicated in the prior art or in the appended claims.

I claim as my invention:

1. In a radio system, a plurality of modulator tubes, a connection between the cathodes of said tubes, a common connection between the anodes of said tubes, a source of modulating potential, means for connecting the input circuits of said tubes in parallel to said source, and a plurality of high-resistance devices respectively individual to said tubes and respectively connected between the grids thereof and their common connection to said source of modulating potential.

2. In a wave transmission system, a plurality of oscillator tubes, a connection between the cathodes of said tubes, a common connection between the anodes of said tubes, an oscillatory circuit, means for connecting the input circuits of said tubes in parallel to

said oscillatory circuit and a plurality of high-resistance devices respectively individual to said tubes and respectively connected between the grids thereof and their common connection to said oscillatory circuit.

- 5 3. In a wave transmission system, a plurality of modulator tubes, a plurality of oscillator tubes, a common connection between the anodes of all of said tubes, a common connection between the cathodes of all of said tubes,
10 an oscillatory circuit, means for connecting the input circuits of said oscillator tubes in parallel to said oscillatory circuit, a source of modulating potential, means for connecting the input circuits of the modulator tubes in parallel to said source, and a plurality of high-resistance devices respectively individual to the input circuits of said tubes and respectively connected between the grids of
15 the oscillator tubes and the oscillatory circuit and the grids of the modulator tubes and the source of modulating potential, whereby the generation of oscillations at parasitic frequencies is prevented.

20 25 In testimony whereof, I have hereunto subscribed my name this 21st day of January, 1924.

DONALD G. LITTLE.
